WAGON

Roy E. Choate and Waldo E. Rodler, Cedar Rapids, Iowa, assignors to La Plant-Choate Mfg. Co. Inc., Cedar Rapids, Iowa, a corporation of Delaware

Application February 27, 1932, Serial No. 595,578

4 Claims. (Cl. 298—35)

This invention relates to vehicles for the haulage of bulky materials such as earth, coal, snow, ice, and the like, and for objects of any kind which will move freely by their own weight, and has particular relation to a means of opening and closing doors or the like, in the vehicle to permit the materials to be received and discharged therefrom.

It is becoming customary, in hauling dirt and like materials, to employ a wagon in the form of a trailer which may be attached to a tractor or truck so that the tractor or truck may haul a large quantity of material at one time using only one operator. There may even be a plurality of trailers employed.

Some of the tractors and trucks are provided with hydraulic pumps whereby the motors used in driving them may also be used to furnish power to a hydraulic jack or the like for operating devices on the truck or tractor, or for furnishing power to actuate other devices from the tractor.

The wagons and trailers are usually provided with doors in the bottom or in the sides so that material deposited in the wagons may be quickly discharged. The doors of these wagons are usually mechanically operated by means of levers, winches, and the like.

The operation of such doors is usually a tedious task and takes considerable time, thereby decreasing the efficiency of the material hauling system. Furthermore, the devices of the prior art are not always satisfactory. Sometimes it is necessary to operate them from the ground, and the wagon cannot be moved until the doors have been placed in position.

We have, therefore, devised an improved mechanical means of opening and closing the doors which may be operated by an operator riding on a platform of the wagon or trailer, and we have also devised a hydraulic means adapted to be removably secured to the wagon and adapted to cooperate with the manually operable device for opening and closing the doors by means of fluid supplied under pressure from the tractor or other device where such power is available.

It is a general object of the invention to provide a new and improved door-operating device.

More particularly it is an object of the invention to provide a combined hand wind and hydraulic lift for opening and closing the doors of a wagon.

A feature of the invention is a manually controllable and operable means for opening and closing the doors and a power means adapted to be removably positioned on the wagon and adapt-

ed to cooperate with the door opening and closing device in order that the doors may be opened and closed by power if desired.

Other and further features and objects of the invention will be more apparent to those skilled in the art upon a consideration of the accompanying drawings and following specification, wherein is disclosed a single exemplary embodiment of the invention, with the understanding, however, that such changes may be made therein as fall within the scope of the appended claims without departing from the spirit of the invention.

Referring now to the drawings in which like numbers indicate like parts:

Figure 1 is a view in perspective of a trailer provided with our new and improved means of opening and closing the doors thereof, and showing the hydraulic device in cooperative engagement with the manual device.

Figure 2 is a view in perspective of the connection between the hydraulic operating means and the manual operating means. A portion of the connecting mechanism has been broken away to show the inner construction thereof.

Figure 3 is a view partly in section and partly in elevation of the connecting device taken along the line 3—3 of Figure 2.

Figure 4 is a view in perspective of the hydraulic jack used in opening and closing the doors and also of a portion of the door-supporting structure. The view is enlarged in order to show the device in greater detail.

Figure 5 is a view in perspective of the manually operative device utilized for opening and closing the doors.

Figure 6 is a view partly in section and partly in elevation of the levers and ratchet mechanism utilized in operating the device shown in Figure 5.

Figure 7 is a view partly in elevation and partly in section of the device shown in Figure 6, but as it appears at a different step in the cycle of operation thereof.

Figure 8 is a view in perspective showing how its doors are hinged and held with respect to the body and frame of the trailer and showing also the pulleys and supports utilized in opening and closing the doors.

Figure 9 is a view in perspective of a portion of the door opening and closing mechanism and showing particularly the pulleys and cables utilized for this purpose.

While the invention has been shown and described in connection with a wagon or trailer

adapted to be hauled by a motor vehicle, such as a truck or tractor, it is quite apparent that the invention is equally applicable to trucks and the like in which the motive power is incorporated directly in the truck. In fact, it is quite possible that an auxiliary motor and steering mechanism might be fitted to the trailer shown without great change in the structure thereof.

Referring to the drawings and particularly to Figure 1, there is shown generally a wagon or trailer 10 comprised of a heavy, substantially rectangular frame 11 upon which a metal box 12 is mounted. The frame may be mounted upon wheels in any desired manner, but a preferred construction employs pairs of cylindrical wheels 13 on each side of the wagon which are secured to the frame 11 by any suitable mounting device, and having link treads 14 mounted on the wheels so that the wagon may be hauled over soft and uneven ground. The wagon box 12 may be of any desired construction, but is preferably comprised of heavy metal plates 15 held in place by angle irons 16 and corner irons 17 so as to form a substantially rectangular box, having flared or sloping side walls. The box is preferably flanged and flared outwardly at its upper edge 18 and provided with heavy joining members 19 in order to carry the load and to hold the box in shape and resist impact from the shovels used in filling the box.

One side of the box is preferably lower than the other to permit loading the wagon from an elevating grader or the like. The wagon is provided with couplers 21 of any suitable type at the front and rear thereof by which it may be towed and in order that other wagons or equipment may be towed by the wagon in turn. A step 22 is provided at the rear end of the trailer so that an operator may step up from the ground to the step and thence to a platform 23, formed by the extending portion of the frame 11, so that he may operate the hand wind mechanism.

The hand wind mechanism, shown more particularly in Figures 2, 3, 5, 6 and 7, is adapted to haul in and release one or more cables such as the cables 26 and 27. The hand wind includes a cylinder 28 mounted for rotation on brackets 29 and 30 which are fastened to the angle irons 16 at the rear end of the wagon. The angle irons may be attached in any suitable manner as by means of the bolts 31. The cylinder 28 is divided by a partition 34 into two parts or drums 32 and 33. The partition has a longitudinally extending flange portion 36 with openings therein to permit the cables 26 and 27 to pass through the flange 36 so that they may be secured to one another and to the drum by means of clamps 37. A circular flange 38 at one end of the cylinder prevents the cable 26 from running over too far to the right, while a flange and the ratchet wheel 39 prevent the cable 27 from winding too far to the left.

The drums 32 and 33 are rotated by means of a ratchet wheel 41 located on the end of the shaft 40 upon which the winding drum 28 is mounted, and the ratchet wheel is rotated by means of a long lever arm 42 which is provided with a pawl 43, shown more particularly in Figure 6. The pawl 43 is a part of the lever arm 42, and the lever is slotted as at 44 so that it may be moved in and out with reference to the shaft 40. If it is desired to rotate the ratchet wheel 41, the lever 42 is picked up and moved upwardly until it slides inwardly toward the shaft 40 by reason of the slope of the slot 44,

until the pawl 43 engages the teeth of the ratchet 41. The operator then pushes the lever downwardly to rotate drum 28. In its normal disengaged position, the lever 42 hangs downwardly, and consequently the pawl 43 is out of engagement with the ratchet wheel 41.

Inasmuch as the load on the cables 26 and 27 tends to cause rotation of the drum 28, according to the direction in which the cables are wound, it is necessary to prevent rotation by means of a locking device such as shown in Figure 7. This locking device comprises a lever 46, having a slotted end 47, in order that the lever may be pivotally secured, by means of a pin 48 and nut 49, to a suitable bracket 51, which is an integral part of the bracket 30.

Other ear-like portions of the slotted end 47 of the lever 46 are provided with corresponding openings in which a pin 52, secured by a nut 53, may be located, and the pin 52 is provided with a pawl 54 adapted to engage the teeth of the ratchet wheel 39. A centrally disposed enlarged portion of the lever 46 is drilled and tapped in order that a set screw 57 may be threaded into the lever 46 with the head of the screw projecting inwardly from the lever. A support 56, attached to and a part of the left hand bracket 30, acts as a support so that when the lever 46 is in its normal down position the lever is prevented from resting on the ratchet wheel 39. By means of the structure described and when the drum is rotated counterclockwise, as by means of the lever 42, the pawl 54 will ride over the teeth of the ratchet wheel 39 to permit it to rotate, but when the pressure upon the lever 42 is released the pawl will engage the teeth of the wheel and prevent rotation of the drums in a clockwise direction under the influence of the load on the cables. It is to be noted that the lever 46 between pins 48 and 52, the pins and the dog 54 constitute a toggle relationship which is in locked position when the lever is down.

When it is desired to release the dog from the ratchet wheel to permit it to rotate in a clockwise direction to release the load, the lever 46 is raised. The raising of the lever causes the pawl 54 to be rotated about the pin 52 until the pawl is to the right of the center line defined by the pins 48 and 52, thus throwing the toggle relation to permit the pawl 54 to swing downwardly and thereby release the ratchet wheel 39.

In operating the hand wind, the operator mounts to the platform 23 by means of the step 22, and holds himself in that position by means of the handhold 58; then raises the lever 42 to a position above the horizontal so that the lever slides downward on the shaft 40 at the slot 44 and the pawl 43 engages the ratchet wheel 41. He then pushes down on the lever 42 which rotates the ratchet wheel 41, and hence winds up the drum 28 to a counterclockwise direction. The dog 54 on the lever 46 slides over the teeth of the ratchet wheel 39 as the wheel 39 is rotated. The operator rotates the lever 42 until it almost strikes the frame 11, and then lets it move backward until the dog 54 engages the teeth of the ratchet wheel 39. He then permits the lever 42 to slip downward so that the pawl 43 is out of engagement with the wheel 41. He then raises the lever 42 and starts a new cycle of operation to wind up the drum 28. This operation is repeated until the doors, hereinafter described, are closed. The car is then filled with material which may be transported as desired.

When it is necessary to discharge the contents

of the trailer, the operator has only to raise the arm 46, thus disengaging the pawl 54. The toggle arrangement of the pawl 54, lever 46 and the pins 52 and 48 permits the pawl 54 to be disengaged from the ratchet wheel without violent or unforeseen movement of the lever 46. Since the cables 26 and 27 may support the entire load of material within the trailer, it is very important that disengagement and release of the drums 10 be gradual so that the operator cannot be injured nor the mechanism damaged.

Since the support or pad 56 and the bracket 51 upon which the lever 46 is mounted are all integral parts of the bracket 30, the hand wind 15 may be fastened to and removed from the wagon as a unit and the parts thereof will always be in alignment.

The hydraulic mechanism is better shown in Figures 1 and 4, and this mechanism comprises 20 generally a jack 61 which is adapted to be removably secured to the flared side of the car opposite to the side from which the car is usually loaded, and a reel 107 and shaft 108 which 25 shaft is secured to the rear of the car and is adapted to engage the shaft 40 of the hand wind mechanism, as shown in Figures 2 and 3.

The jack 61 is comprised of a cylinder base 63, having flanged extensions 64 in order that the base may be secured to the angle iron supports 16 on the side of the car, as by means of bolts 66. Another pair of flanges 65 and 67 extend perpendicularly from the base and the flanges are bifurcated to constitute a means for pivotally mounting pulleys 68 and 69 therein. 35 Fanges 71 constitute strengthening means for holding the flanges 65 and 67 in position. A lobed extension 72 of one of the flanges 67 is drilled to afford means for securing a cable 73 thereto as by means of the U-clamps 74, and 40 the flange 72 is strengthened by means of a rib 76. A semi-circular extension 77 of the flange 65 is provided with an opening therethrough in order that the cable 73 may pass through the opening and be directed in a direction parallel to 45 the barrel of the hydraulic jack. Oil or other fluid is introduced into the base 63 through a hose or pipe connection 78, a coupling 79, and a boss 81, which is a part of the cylinder head 63.

The cylinder proper is shown at 82, and this 50 cylinder is, of course, mounted on the cylinder head 63, as by threading it into suitable threads in the cylinder head. A cylinder cap 83 is threaded onto the outer end of the cylinder 82, and the cylinder cap is provided with flanges 84 in 55 order that it may be secured to suitable straps 86 on the side of the box, as by means of bolts 85. The cylinder head is provided with an exhaust opening, and an elbow 88 conducts any fluid or air from within the cylinder out to the 60 atmosphere through a perforated exhaust port 89. The cylinder head 83 is provided with an extension 91 which acts as a guide for a piston rod 92, which acts as a wiper to prevent dirt from entering the cylinder, and which prevents oil 65 from flowing through the cap.

A laterally extending yoke 94 is fastened to the 70 end of the piston rod 92 as by means of bolts 96, and the yoke is provided with pulleys 97 and 98 at either end thereof in order that the cable 73 may be led over the pulley 97 and back over the pulleys 68 and 69 to the other pulley 98 and toward the rear of the wagon. The cable is 75 guided by means of guides 99 to prevent it from coming off the pulleys, and the flanges 77 and 72 act in this capacity for the base 63.

The pipe 78 leads up beneath the flange 18 at the top of the wagon box, to the front of the wagon and down to the platform at the front of the wagon where suitable valves and connections similar to the valve 101, coupling 102 and flexible 5 hose 103 are placed, which valve, coupling and hose are adapted for making hydraulic connection with pumps, control valves and the like on the tractor or truck (not shown). A valve 101 (Figure 1) is provided at the platform 23 in 10 order that hydraulic connection with a second wagon or other trailing equipment may be made and cut off. A coupling 102 leads upwardly from the valve, and a flexible hose 103 leads to a suitable supply line on the second wagon (not shown). 15

The cable 73 is brought rearwardly over a suitable pulley 104 which is fastened to the side of the wagon as by means of a bracket 106, and is led over a wheel or sheave 107 at the rear of the wagon. This sheave is mounted on a shaft 20 108 which is held in place at the rear of the wagon for rotation by means of a bracket 109 secured as by means of bolts 111 to the corner angle iron 17. The end of the cable 73 is secured to the sheave by means of a U-clamp 112 (Figures 1 25 and 2) which passes through suitable openings in the flange 113 of the sheave. The sheave is provided with a helical groove 114 so that the cable will not kink, and a flange 116 at the inner end of the sheave prevents the cable from wedging 30 between the sheave and the bracket 109. The shaft 108 is provided with splines 117 at its inner end in order that a splined sleeve 118 may be utilized to connect the shaft 108 with the end of the shaft 50, which is also splined as at 119. 35 By moving the sleeve 118 to one side the shafts 50 and 108 are disengaged from each other and the shaft 108 may be rotated and the sleeve 118 replaced to compensate for stretching of the cable.

It is apparent that if fluid is introduced from 40 the tractor or truck by means of the flexible hose, the coupling and the valve at the front of the wagon, the piping 78 and the coupling 79, into the base 63 of the hydraulic jack 61, the piston rod 92 will travel to the right and will cause the 45 cable 73 to be drawn up in much the same manner as the end cable of a block and tackle system is drawn by increasing the distance between blocks. In fact, the pulley system here shown is substantially the same as that of a block and tackle system, and works in the same way—one end of the cable being fastened to a fixed block and the hydraulic jack being the means used for lengthening and decreasing the distance between the blocks. 55

It is apparent that the stresses on the jack are uniformly distributed and there is no side thrust on the piston. The device may be readily secured to the wagon and removed therefrom. It requires only one pipe to lead fluid from the coupling at 60 the front of the wagon to the hydraulic jack.

A simple and unique system is employed for mounting the doors on the bottom of the wagon and for opening and closing them by means of the cables 26 and 27. This system is better 65 shown in Figures 8 and 9. The cables 26 and 27 are parts of a single cable, having its ends secured to each other and to the drum 28, as hereinbefore described. The cables 26 and 27 pass down through the end member of the frame 11 and 70 over pulleys 121 disposed within the end member of the frame.

The doors 122 (Figure 8) are long rectangular plates fastened to the underside of the box 12 as by means of chain links 123, one end of the chain 75

being secured by a suitable eye 124 to the rectangular plate and the other being secured to an eye 126 (Figure 4) which is a part of an angular bracing bracket 127 engaging the top of the frame 11 and side of the box 12, being bolted thereto as by means of bolts 128, and the chain passing through a suitable slot 129 in the side of the box. A bracing flange 131 is formed on the inner side of each of the plates 122 in order to support the load, and this flange affords a means for securing an end roller bracket 132 to the door.

This roller bracket is comprised of a housing 133 provided with suitable flanges 134 by which it may be secured to the door as by means of bolts or rivets 136 and the housing 133 is provided with a pin 137 on which a pulley 138 of hour-glass shape is rotatably mounted. The housing 133 has guides 139 extending over the pulley for the purpose of bracing the housing and of guiding the cable. Other brackets 141 are secured to the flange 131 and to the underside of the plates 122 at the midpoint thereof and the pulleys 142 act as guides for the cables 26 and 27. If desired blocks having openings therethrough for the cables may be substituted for the pulleys 142 and the blocks will act as bumpers which strike against suitable portions of the wagon-supporting sub-structure so the doors may be jarred to loosen clinging material. Another set of pulleys 143, similar in construction to the pulleys 132 just described but with their parts in reversed relation, are fastened to the front ends of the doors and project out over the end thereof so that the cable 26 may pass up over a pulley 144 mounted for rotation in a vertical plane on the frame 11 of the wagon. The bracket 146, for supporting this pulley, is secured to any suitable portion of the frame 11. The cables 26 and 27, as has been stated, are in reality one single cable and this cable passes over the pulley 144 to equalize the strain on different parts of the cable. It is plain to be seen that when the cables 26 and 27 are drawn upwardly, the doors 122 will close. On the contrary, if the drum 28 is released, the cables will move downwardly by reason of the weight of the doors 122 and of the load supported by them, and the doors will open. The width of the pulleys 138 and the angle at which they are cut is such that the cables always pull against the bottom of the grooves formed by the converging sides of the pulley, so that the cable does not undergo a rubbing action.

It is apparent that we have provided a new and improved door-opening and closing device and that the device may be applied to a wagon or trailer without altering the construction thereof

and that, if desired, a power-actuated winding device may be supplied at little additional expense. The devices are self-compensating in application of the forces necessary to open and close the doors and the devices used are simple, reliable and strong.

Although we have described one embodiment of our invention, it is apparent that modifications thereof may be made by those skilled in the art and that the invention may be applied to other uses. Such modifications may be made without departing from the spirit and scope of the invention as set forth in the appended claims.

We claim as our invention:

1. In a door opening and closing mechanism for a dump wagon, a winch mounted on one end of the wagon, the winch being disposed so that its axis of rotation is horizontal and parallel to the end of the wagon and means for operating the winch hydraulically comprising a hydraulic jack, a cable leading from the hydraulic jack, a shaft disposed to be removably connected to the shaft of the winch and means for rotating the last-named shaft by means of the cable from the hydraulic jack.

2. In a dump wagon, doors mounted in the bottom thereof, for pivotal movement about horizontal axes, a winch mounted on one end of the dump wagon, a cable extending from the winch to the doors for closing them, a shaft mounted for removable connection to the winch, a hydraulic jack at one side of the wagon and means for connecting the hydraulic jack with the shaft to rotate it to operate the winch.

3. In a wagon including a wagon box, doors on the wagon box, means for closing the doors comprising a winch disposed on the end of the wagon and including a shaft, a power means for actuating the winch and including a shaft rotatably mounted on the same axis as the shaft of the winch, and means for removably engaging the last-named shaft with the first-named shaft.

4. In a dump wagon having doors, a winch for opening and closing the doors, the winch having a shaft projecting therefrom, a hydraulic jack system for operating the winch comprising a hydraulic jack, a cable leading from the hydraulic jack, a shaft disposed to be removably connected to the shaft of the winch, and a means for rotating the shaft by means of the cable from the hydraulic jack, and a coupling means for cooperatively engaging the shaft of the winch to the last-named shaft to permit the hydraulic system to operate the winch when desired.

ROY E. CHOATE.
WALDO E. RODLER.
